UNITED STATES PATENT OFFICE.

THOMAS P. HARBOUR AND BURLEIGH B. BRINNON, OF BELLEFONTAINE, OHIO.

COMMUTATOR.

1,353,392.

Specification of Letters Patent. Patented Sept. 21, 1920.

Application filed September 19, 1919. Serial No. 324,762.

To all whom it may concern:

Be it known that we, THOMAS P. HARBOUR and BURLEIGH B. BRINNON, citizens of the United States, residing at Bellefontaine, in the county of Logan and State of Ohio, have invented certain new and useful Improvements in Commutators, of which the following is a specification.

This invention relates to improvements in commutators especially adapted for use on internal combustion engines in connection with the ignition system of the same.

An important object of this invention is to provide a commutator having novel means for pressing the rotary contact into engagement with the stationary contacts with a uniform degree of pressure whereby a good electrical connection is provided between the rotary and stationary contacts.

A further object of this invention is to provide a commutator having novel means for connecting the rotary contact to the operating shaft whereby the rotary contact may be readily removed for the purpose of cleaning etc.

A further object of the invention is to provide a commutator having novel means for uniformly pressing the rotary contact into engagement with the stationary contacts whereby the use of lubricants in the commutator might be dispensed with.

A further object of the invention is to provide a commutator which is efficient, of highly simplified construction and cheap to manufacture.

Other objects and advantages will be apparent during the course of the following description.

In the accompanying drawing forming a part of this application and in which like numerals are employed to designate like parts throughout the same:

Figure 1 is a front elevation of a commutator having the improved rotary contact applied to the same;

Fig. 2 is a perspective of the improved rotary contact and associated elements;

Fig. 3 is a perspective of the commutator having a modified form of rotary contact.

In the drawing wherein for the purpose of illustration is shown a preferred embodiment of the invention, the numeral 5 generally designates a conical cover having an annular band 6. A plurality of binding posts 7 extend through the annular band 6 and have connection with feed wires 8 which

extend to spark plugs of an internal combustion engine. An arm 9 is secured to the shell and has pivotal connection with an operating lever 10 through the medium of a 60 pin 11. The operating lever 10 is adapted for adjusting the commutator casing 5 to either retard or advance the spark in the motor as desired.

The binding posts 7 extend through an 65 annular insulator 12 arranged within the band 6 and having embedded therein a plurality of spaced relatively stationary contacts 13.

In the form of our invention illustrated 70 in Figs. 1 and 2, a split collar 14 is arranged about one end of a cam shaft 15' and is adapted to be securely attached to the same by a screw bolt 15 which is extended through a pair of apertured ears 16. A plurality of 75 flat leaf springs 17 are secured between the apertured ears 16 and are rigidly held in position by the screw bolt 15. A rotary contact brush 18 is mounted on the outer end portion of the springs 17 and is provided 80 with a pair of attaching arms 19 which extend through the springs 17 and are bent upon the same for securely connecting the outer ends of the springs 17 and positioning the brush. The springs 17 have their 85 outer end portions curved transversely as indicated at 20 for squarely presenting the curved outer side 21 of the brush 18 to the stationary contacts 13. During the rotation of the cam shaft 15', the brush 18 is forced 90 into uniform engagement with the contacts 13 by the action of the springs 17 and by centrifugal force. The uniform pressure on the brush 18 causes the contacts 13 and the surface of the annular insulating member 12 to wear evenly and thereby greatly 95 prolongs the life of the commutator. The springs 17 and the brush 18 may be of any suitable material capable of conducting the electrical current. The uniform contact between the rounded surface 21 of the brush 18 and the stationary contacts 13 dispenses with the necessity of employing oil for lubricating the commutator.

In the form of the invention illustrated in 105 Fig. 3 an attaching collar 22 is adapted to be arranged on a cam shaft 23 and is provided with a longitudinally extending slot 24 receiving a locking key 25 carried by the cam shaft. An ear 26 is formed on the 110 outer side of the collar 22 and has the leaf springs 17 connected thereto by a screw bolt

27. In this form of the invention the screw bolt 27 extends through alining openings in the springs 17 and the ear 26 and serves to detachably secure the springs 17 in position.
- 5 As in the form of the invention illustrated in Fig. 1, the brush 18 is mounted on the outer end portions of the springs 17 and is caused to engage the contacts 13 with a uniform degree of pressure.
- 10 In the practice of the invention, the collars are arranged on the cam shafts and the springs 17 are subsequently secured to the collar. The application of the commutator casing brings the outer curved surface 21 of
- 15 the brush 18 into engagement with the stationary contacts 13. During the rotary movement of the contact 18, the curved outer surface of the same is presented to the stationary contacts and by reason of the uniform pressure exerted by the springs 17, a good electrical contact is provided between the stationary and rotary contacts. The curved outer surface of the contact 18 also causes the stationary contacts and the inner surface of the insulator 12 to wear evenly and eliminates the necessity of lubricating the commutator.
- 20 Having thus described the invention, what is claimed as new is:
- 25
- 30 1. A commutator including a rotary member, a plurality of leaf springs detachably secured at their inner end portions to said rotary member, the outer end portions of said leaf springs being provided with openings, and a contact having a pair of attaching arms extending through the openings in said springs and being bent upon the same for connecting the leaf springs and supporting said contact.
2. A commutator including a rotary member, a plurality of superposed longitudinally curved leaf springs having connection with the rotary member and having their outer portions provided with alined apertures, a contact arranged at the outer portions of said leaf springs and having attaching means formed integral therewith and extending through the apertures in said leaf springs, and a plurality of stationary contacts adapted to be engaged by said first named contact.
3. A commutator including a shaft, a split collar arranged upon the shaft and having its ends provided with spaced apertured ears, a plurality of leaf springs having their rear end portions apertured and arranged between said apertured ears, a fastening device extending through said apertured ears and said leaf springs for connecting the springs and for securing the collar rigidly to the shaft, and a contact element carried by the outer portions of said leaf springs and having means for connecting the same.
- In testimony whereof we affix our signatures.
